(57) CLAIM

The ornamental design for a purse, as shown and described.

DESCRIPTION

FIG. 1 is a perspective view of a purse showing our new design;

FIG. 2 is a perspective view thereof showing the side flap extended upward with cans shown in broken lines disposed in the side pockets;

FIG. 3 is a perspective view showing the top flap collapsed covering the cans in the inside pockets;

FIG. 4 is a side view thereof;

FIG. 5 is a end view of thereof;

FIG. 6 is a bottom view of the purse in an expanded view;

FIG. 7 is a top view thereof;

FIG. 8 is a perspective top view thereof showing cans in broken lines disposed in the pockets therein; and,

FIG. 9 is bottom view of the purse in the collapsed view. The broken lines in the drawings represent stitching and are part of the claimed design.
